Primary Examiner—Doris Clark
Attorney, Agent, or Firm—Goldstein & Canino[57] **CLAIM**

The ornamental design for a free standing garage screen door, as shown and described.

DESCRIPTION

FIG. 1 is a diagrammatic elevational view of a free standing garage screen door in full lines with a house shown in broken lines representing environmental association matter being for illustrative purposes only and forming no part of the claimed invention.

FIG. 2 is a front elevational view of the free standing garage screen door, the rear elevational view being a mirror image of the front view.

FIG. 3 is a left side elevational view thereof, the right side elevational view being a mirror image of the left side view.

FIG. 4 is a top plan view thereof; and,

FIG. 5 is a bottom plan view thereof.
